United States Patent Office

Des. 192,304
Patented Feb. 27, 1962

192,304

REFUSE RECEPTACLE

Roy R. Dylla, 3649 W. Armitage Ave., Chicago 47, Ill.

Filed Apr. 20, 1961, Ser. No. 64,837

Term of patent 14 years

(Cl. D58—17)

FIG. 1

FIG. 2

FIG. 3

FIG. 5

FIG. 4

FIG. 1 is an isometric view of a refuse receptacle embodying my new design;

FIG. 2 is a front elevational view thereof;

FIG. 3 is a side elevational view thereof;

FIG. 4 is a top plan view thereof; and

FIG. 5 is a rear elevational view thereof.

I claim:

The ornamental design for a refuse receptacle, substantially as shown.
